OIL BURNER INSTALLATION

Lynn O. Selby, Cromwell, Conn., assignor to The
Sparmal Engineering Corporation, a corpora-
tion of Connecticut

Application May 23, 1940, Serial No. 336,791

5 Claims. (Cl. 236—6)

My invention relates to oil burner installations. It has among its objects to provide an improved brooder installation of the oil burner type and, more particularly, such an installation having improved heating and controlling means. A further object of my invention is to provide such an improved installation including a distillate burner in combination with an improved temperature responsive valve mechanism governing the supply of fuel to such a burner in an improved manner and capable of maintaining the temperature range in the brooder within much narrower limits than has hitherto been possible. Another object of the invention is to provide such an improved brooder installation having a brooder hood enclosing heat generating means and having improved thermo-responsive means for governing the latter, these improved means herein cooperating with an improved valve and improved gravity feed means maintaining a substantially constant pressure head and being so situated relative to the brooder hood that said thermo-responsive means are acted upon by the stream of air circulating under the hood, all in such manner as to make possible a more sensitive control of the heating means and a closer regulation of the temperature under the hood. Still another object of the invention is to provide an improved thermostatically controlled oil burner installation including a distillate type oil burner, i. e. a burner having a so-called "carbon leg," or vaporizer, for supplying vaporized fuel to the burner base during normal operation, and wherein it is made possible to automatically control the fuel supply to the burner in response to temperature changes in such an improved manner as to obtain new and markedly improved results. These and other objects of my invention will, however, hereinafter more fully appear.

In the accompanying drawings I have shown for purposes of illustration one embodiment which my invention may assume in practice.

In these drawings:

Figure 1 is a sectional elevation of a brooder house taken on line 1—1 of Figure 2 and showing my improved brooder therein in side elevation;

Fig. 2 is a sectional plan view of the brooder installation of Figure 1;

Fig. 3 is a sectional elevation on line 3—3 of Figure 2;

Fig. 4 is a sectional elevation of the thermostatically controlled valve and the adjustable supporting means therefor;

Fig. 5 is an enlarged detail view showing the

position of the temperature responsive element of the valve relative to the brooder and enclosure;

Fig. 6 is a diagrammatic side elevation, partly broken away, of the fuel supply, burner and controlling mechanism therefor;

Fig. 7 is a plan view of the base of the burner of Fig. 6 with the wicks and shells removed therefrom to facilitate illustration, and

Fig. 8 is a detail vertical section taken on line 8—8 of Fig. 7 with the wicks and shells thereon.

The illustrative brooder installation embodying my invention includes a brooder house A comprising a single brooder room, access to which is gained through a door 2 located in one side of the house adjacent the front thereof. A brooder B is located on the floor 3 of the house midway between the side walls thereof and slightly to the rear, and preferably to the north, of the center of the room.

This brooder, which is of a more or less usual construction, includes a stove 4 supported on suitable legs 5 in spaced relation above the floor 3. The stove 4, in turn, carries at its upper end and closes the top of a depending annular brooder hood 6 which encloses a substantial part of the heating surface of the stove. This hood is preferably of sheet metal and has the lower annular rim 7 thereof spaced vertically above the floor 3 in a customary manner to permit the chickens to circulate freely therebeneath. The stove 4 also has a fire door 8, and a hinged peripheral flap 9 is provided in the hood in alignment therewith permitting access to the interior of the stove. A flue 10 is also provided for said stove which is extended laterally through the hood 6 and thence upwardly through the roof of the house.

The temperature in the house A is controlled in a new and effective manner in accordance with my invention, wherein the temperature is maintained within very close predetermined temperature limits by means including a distillate type oil burner, i. e. a burner having a vaporizer for supplying vaporized fuel to the burner base under the control of an improved valve having an improved temperature-responsive device located in a usual position relative to the fuel supply reservoir and brooder hood and cooperating with improved gravity feed means maintaining a substantially constant pressure head, to govern the flow of fluid to the burner in an improved manner.

As shown most clearly in Figures 6, 7 and 8, the burner installation includes a fluid receptacle 11, or burner base usual in distillate burners, lo-

cated within the stove 4 and supported above the bottom 12 of the combustion chamber thereof by a single vertically adjustable leg 13 comprising overlying slotted members which are clamped together in the desired adjusted position by a clamping bolt 13a. The burner supporting leg 13, carrying the base 11 at its upper end, is provided with radially extended feet 14 and is fixed to the stove bottom 12 by a clamping bolt 15. Leveling screws 16 are threaded into the feet 14 adjacent the extremities thereof and bear against the upper surface of the stove bottom 12. The burner base 11 supports the usual perforated shells, shown at 17 and forming combustion chambers, and usual starting wicks 17a disposed in usual burner grooves 17b between and below the shells 17, usual air passages 17c also being provided in the base 11 and surrounded by the grooves 17b, for supplying air upward along the shells 17. Oil, or other liquid fuel, is supplied to the base 11 through a vertically adjustable "carbon leg," or fuel vaporizer, 18 secured to the base 11 and supplied with oil from a reservoir C through a pipe line 19; the "carbon leg" acting to vaporize the fuel and generate gas in the manner usual in distillate burners of the type shown herein, in which the wicks are used only in starting, and the liquid fuel, after starting, is vaporized in the "carbon leg," and thereafter passes in the form of vapor into the hot burner base and between shells 17 in a usual manner, being distributed radially through usual covered radial passages 17d. While the distillate burner illustrated is of the construction shown in the Williams Patent No. 1,911,661, it will be understood that this is only illustrative and that various other standard forms of distillate burners, likewise heretofore only manually controllable as to temperature, may be used, for example, that shown in the Nest et al. Patent No. 2,008,151.

The oil receptacle C can be of any type which will supply fuel to the burner under a substantially constant pressure and herein is of the well known type in which the fuel is fed to the burner by gravity and the oil in the receptacle is open to the atmosphere and is maintained at a constant level. As here shown, the receptacle C is supported above the floor of the brooder house on legs 20 which are vertically extensible whereby to adjust the level of the oil in the receptacle relative to the burner base 11, it being understood that means are provided for replenishing the supply of oil in the container C as it is withdrawn by which the level of the oil in the container C is maintained at a constant level. This is accomplished by the use of a well known inverted bottle 21, the open mouth 22 of which extends below the open top of the oil receptacle C and is immersed in the liquid therein, a suitable seat 23 being provided for the bottle at the top of receptacle C while permitting the receptacle free communication with the atmosphere.

In starting the burner, a body of oil is supplied to the burner base 11 to a depth of approximately three-sixteenths of an inch as indicated by the line 24a in Figure 6; the oil level in the container C being maintained approximately three-sixteenths of an inch above the bottoms of the grooves 17b in the burner, whereby to provide sufficient head of oil in the container to supply oil to the burner in a manner usual in the art. Attention is further directed to the fact that this head of oil is substantially constant, i. e., with the level in the receptacle C, which forms a supplemental reservoir between

the main reservoir or bottle 21 and the burner, maintained substantially constant in such manner as to make it possible to maintain a constant supply to the burner in any given position of the valve D hereinafter described. Here, of course, it will also be understood that when the burner is operating, the oil therein will be consumed at a rate dependent upon the position of the valve, with increased vaporization of the oil supplied to the carbon leg occurring as the burner approaches full "on" operation. Even if improperly operated, the risk of fire is minimized, it being evident that the oil can never rise to a level where it will overflow the burner base, and consequently the danger of flooding the brooder room floor with burning oil is minimized.

A thermostatically controlled valve D is herein provided in the pipe line 19 between the oil container C and the burner base 11 and herein operates to control the amount of oil flowing through the pipe line 19 under the substantially constant pressure head referred to above. This valve is of the type more fully described in my copending application, Serial No. 759,196, filed December 26th, 1934, and reference may be had to said application for a more complete disclosure thereof.

In general, the valve D (Fig. 4) comprises a body portion 25 which is vertically adjustably supported relative to the floor 3 of the brooder house by means of a pedestal 26 fixed to the floor and telescoping rod 27, the latter of which is screw threaded into the valve body 25. Said valve body 25 is provided with a horizontal oil passage 28 therethrough having a central cylindrical passage 29 of reduced diameter. Oil is supplied to the righthand end of said passage 28 as viewed in Figure 4 from the oil container C through the pipe line 19 and leaves the lefthand end of said passage 28 through a vertical passage 30 and a throttling, or so-called metering valve, 31 which is connected to the section of the pipe line 19 leading to the burner base 11 and determines the maximum amount of oil which can be supplied through the pipe line 19 to the burner. The valve body 25 is also provided with a long, upstanding stem 32 having a vertical annular passage 33 therein which intercepts the horizontal oil passage 29 and in which passage 33 a reciprocable plunger type valve member operates under the influence of a vertically expandable bellows type thermostat 34. Said thermostat 34, which is of the type adapted to contain a thermally expandable fluid that is highly volatile throughout the temperature range at which the device is to operate, carries at its upper end a screw threaded stud 35 which is supported by the top 36 of an inverted U-shaped member, the free ends 37 of which are rigidly secured to a tubular extension 38 of the upstanding stem 32. A connecting rod 39 is adjustably screw threaded into a coupling member 40 carried by the lower wall of the bellows 34 and is connected at its lower end by a universal ball and socket connection 41 to a plunger 42 reciprocable within the passage 33. Thus it will be observed that, while air may escape from the oil line up along the plunger in such manner as to avoid air locks, the plunger 42 is suspended from the bellows 34 and buoyed up at its lower end by the oil in the passage 33. Said passage 33 is closed at its lower end by a vertically adjustable screw 43 having a conical, pointed, upper end comprising a seat on which the lower end of the plunger 42 is adapted to rest in its lowermost

position in which the horizontal passage 29 is almost closed by said plunger, the screw 43 being adjusted so that only sufficient oil can pass by the plunger 42 to maintain a low pilot flame in the burner.

It will thus be evident that in my improved installation fuel will be admitted to the burner through the valve D under the control of the bellows 34 and in accordance with the temperature requirements as determined by the setting of the valve and bellows. Further, even if a sudden reduction in temperature occurs, increased amounts of fuel will be supplied gradually to the burner, due to the inherent gradual response to temperature changes characteristic of such thermostats utilizing a highly volatile expansible fluid, and resulting from the rate of heat conductivity through such a volatile medium. Thus, even in the case of such a sudden reduction in temperature, while the response to the temperature change begins promptly, the flow of fuel is so modulated as to avoid both a fuel surge and the feeding of fuel faster than the vaporizing ability of the carbon leg is increased as the temperature of the burner increases. The desired minimum temperature setting of the valve is first obtained roughly by adjusting the nut 44 on the stud 35 to raise and lower the bellows against the pressure of a spring 44a and thus raise and lower the connecting rod 39 and the plunger 42. A further, and finer, adjustment is provided by means of a knurled wheel 45 fixed to the connecting rod 39 and by which the latter can be rotated to screw the same into and out of the coupling member 40 and thus raise and lower the plunger 42 relative to the bellows. Accordingly, with the parts properly adjusted, the valve will function automatically gradually to vary the fuel supplied to the burner between the maximum and minimum limits of vaporization of the vaporizer at different burner temperatures, as established by the metering or throttling valve 31 and the screw 43 to maintain the predetermined temperature desired.

In accordance with the illustrative embodiment of the present invention, the valve D is supported by means of its pedestal 26 on the floor 3 of the brooder house beneath the hood 6 and closely adjacent the lower peripheral rim of the latter. As shown most clearly in Figures 1 and 5, the valve is so located relative to the rim of the brooder hood that the bellows 34 thereof is located just below the rim 7 and slightly laterally spaced inwardly from the latter to provide a space 46 between the bellows and the rim 7. In practice, this space 46 is very short, about one-eighth of an inch being found to be very satisfactory. It will further be noted that the fuel pipe line 19 drops slightly downwardly from the burner to the valve D so that the controlled portion of passage 29 is at the lowest point in the line between said passage and the burner, and that, as shown in Fig. 6, the passage 29 is the lowest in the installation although the section of the pipe line 19 between the valve D and the reservoir C can be carried down below the floor 3 of the brooder house as illustrated in Fig. 1, if desired, thus leaving an unobstructed passage around the hood 6 for cleaning, etc. It will also be noted that the oil reservoir C is located adjacent the door 2 so that the oil supply can be replenished without disturbing the chickens in the brooder house.

By reason of my improved construction it will be noted that my improved thermo-responsive

valve is so disposed in the pipe line connecting the burner base 11 and the receptacle C that it is enabled to cooperate therewith in an improved manner to enable improved results to be obtained. 5 Thus, it is made possible in my improved construction for a constant pressure head to be maintained on the fuel supplied to the burner while the valve is enabled to function wholly independently of the level in the receptacle C which, in my improved construction, is maintained substantially constant in all positions of the valve. Further, it will be noted that the valve also functions only in response to temperature changes and wholly independently of the oil consumption or the level in the burner base 11. Thus, it is made possible not only to eliminate all need for connecting a float to the valve but also to eliminate any connection of the thermostat to a float, and the operation of the float by the thermostat. Instead, in my improved construction the thermostat is required only to operate the valve. Moreover, due to the improved operative connections between the thermostat and the valve and the improved construction of the valve, it will be evident that the mechanism is exceedingly sensitive, with the end of the valve plunger which moves transversely of the passage 29 being very sensitively adjusted automatically as the temperature changes cause expansion or contraction of the expansible fluid in the thermostat bellows. Attention further is directed to the fact that as a result of my improved construction, it is also made possible not only for the valve to be outside the supplemental reservoir, but to have the latter disposed at any selected remote point, as, for example, outside the brooder hood. Herein, it is also made possible for the valve casing to carry the thermostat and all mechanism operated thereby, as distinguished from, as in certain prior art constructions, the thermostat being carried by the supplemental reservoir. Further, by the location of the improved thermostatically controlled valve in the supply line with the bellows 34 thereof located just below the rim 7 of the hood and slightly laterally spaced from said rim 7, it will be observed that the bellows 34 is located directly in the circulating stream of air set up beneath the hood due to the presence of the heating stove 4. It will be further be noted that this bellows is located in the downwardly directed portion of said circulating air stream just prior to the sweeping of the same on the floor 3 of the brooder house. Here it will be observed that air coming in contact with the hot sides of the stove 4 becomes heated and rises, striking the cooler surfaces of the hood. The heated air is then swept downwardly along the inner surface of the hood, partly by the pressure of hotter air rising adjacent the stove and partly by reason of the fact that it is gradually cooled while in contact with the hood surface. This natural circulatory movement of the air beneath the hood causes the outer and downwardly directed portion of the air stream, which has become somewhat tempered by this contact with the hood surfaces, to sweep over the brooder floor and maintain an enlarged zone of increased temperature beneath and surrounding the hood, it being noted that this warm air is directed downwardly at the angle of slope of the hood 6 and consequently provides a zone of increased temperature which extends somewhat beyond the periphery of the hood.

It will be noted that as a result of my inven-

tion it is for the first time made possible to control a distillate type installation automatically in response to temperature while maintaining the burner, its reservoir, and the fuel level stationary relative to each other. In this connection, it will also be particularly noted that it is made possible to eliminate the drip feed used in previous attempts to provide automatic temperature responsive fuel control for oil burners, and which, while suitable for use with wick or 10 pot type burners, is wholly unadapted for use with the more sensitive distillate burners wherein intermittent and objectionable flaring and resulting carbonization is produced as the level of oil in the carbon leg is intermittently raised by said drops and each new increment of oil supplied to this carbon leg is instantly vaporized therein. Further, with the gentle flow arising from a constant low pressure head, there is a 15 minimum of interference with the sensitiveness of the extremely sensitive temperature control provided. Also, the two combine to make possible minute variations in the amount of fuel to be vaporized by the distillate burner and prompt vaporization in response to relatively minute changes in temperature while maintaining a continuous feeding of fuel. Thus, under all operating conditions, it is possible to feed to the 20 burner only such a volume of oil as the burner can vaporize, as distinguished from causing flaring and carbonization due to the presence of unvaporized oil in the flame, and thereby obtain not only a markedly improved burner operation, but a markedly sensitive and effective control 25 for such a highly sensitive burner. As a result, it is made possible to obtain thermostatic control of a distillate burner, as distinguished from manual control, and thereby for the first time make it possible to obtain the advantages of the 30 high operating temperature and clean operation characteristic of such distillate burners which, due to the sensitivity thereof were previously obtainable only in manually controlled installations such as the usual range burners shown in the Williams patent mentioned. It will also be 35 understood that my invention in certain of its broader phases is not limited to use with brooders, but may be used generally in connection with distillate type oil burners in other relations while continuing to obtain new and markedly 40 advantageous results as regards extreme sensitivity of operation for maintaining any selected temperature within chosen limits. Thus, my improved combination, including a thermo-responsive valve in the liquid fuel supply line and with the thermo-responsive means thereof responsive only to temperature changes and free from control by the liquid level in the burner base or in the supplemental reservoir, and with the thermo-responsive valve acting upon a fuel 45 supply which is maintained under a substantially constant pressure head, is adapted to use in connection with room heaters of various other types than the brooder house illustrated, and also to use in various other heating installations, irrespective of whether the thermo-responsive means is responsive to changes in atmospheric temperature surrounding the same, or has the temperature of the expansible fluid therein raised or lowered by other means. While adapted to use with medium or large size distillate burners having plural grooves such as illustrated, wherein a metering valve is preferably used, it 50 will also be understood that my invention is also adapted to use with smaller diameter burners

having single grooves and wherein the metering valve may be replaced by other fuel supply controlling means in the fuel connections having the function of the metering valve in establishing a maximum fuel flow during full operation which is within the vaporizing capacity of the vaporizer or carbon leg. These and other advantages of my improved construction will, however, be clearly apparent to those skilled in the art.

This application is a continuation in part of my copending application filed January 16, 1935, Serial No. 2,075.

While I have in this application specifically 15 described one embodiment which my invention may assume in practice, it will be understood that the same is shown for purposes of illustration and that the invention may be modified and embodied in various other forms without departing from its spirit or the scope of the appended claims.

What I claim as new and desire to secure by Letters Patent is:

1. In combination, a liquid fuel burner of the distillate type having a base and an annular groove therein and a combustion chamber above said groove and upwardly delivering air passage means in said base surrounded by said groove and delivering along said combustion chamber, and also having a vaporizer heated by said base for supplying vaporized fuel to said groove during normal operation, means for supplying liquid fuel to said vaporizer during said normal operation while maintaining a low pressure constant level supply supplying a limited amount of fuel within the maximum vaporizing capacity of said vaporizer when the burner is at maximum operating temperature, and expansible fluid operated temperature responsive valve means operative gradually as temperature changes affect the expansible fluid in said valve means for gradually varying the supply of fuel to said vaporizer during said normal operation while maintaining said supply within the limits of vaporization by said vaporizer at different operating temperatures and maintaining said base and vaporizer at a sufficient temperature during said normal operation to vaporize the fuel being fed to said vaporizer.

2. In combination, a liquid fuel burner of the distillate type having a base and radially communicating annular grooves therein and combustion chambers above said grooves and upwardly delivering air passages in said base between said grooves and delivering between said combustion chambers, and also having a vaporizer heated by said base for supplying vaporized fuel to said grooves during normal operation, means for supplying liquid fuel to said vaporizer during said normal operation while maintaining a low pressure constant level supply including a manually adjustable valve means for limiting the flow of fuel supplied to an amount within the maximum vaporizing capacity of said vaporizer when the burner is at maximum operating temperature, and expansible fluid operated temperature responsive valve means operative gradually as temperature changes affect the expansible fluid in said valve means for gradually varying the supply of fuel to said vaporizer during said normal operation while maintaining said supply within the limits of vaporization by said vaporizer at different operating temperatures and maintaining said base and vaporizer at a sufficient

temperature during said normal operation to vaporize the fuel being fed to said vaporizer.

3. In combination, a liquid fuel burner of the distillate type having a base and radially communicating annular grooves therein and combustion chambers above said grooves and upwardly delivering air passages in said base between said grooves and delivering between said combustion chambers, and also having a vaporizer heated by said base for supplying vaporized fuel to said grooves during normal operation, means for supplying liquid fuel to said vaporizer during said normal operation while maintaining a low pressure constant level supply including a manually adjustable valve means for limiting the flow of fuel supplied to an amount within the maximum vaporizing capacity of said vaporizer when the burner is at maximum operating temperature, and expansible fluid operated temperature responsive valve means operative gradually as temperature changes affect the expansible fluid in said valve means for gradually varying the supply of fuel to said vaporizer during said normal operation while maintaining said supply within the limits of vaporization by said vaporizer at different operating temperatures and maintaining said base and vaporizer at a sufficient temperature during said normal operation to vaporize the fuel being fed to said vaporizer, said supply means to said vaporizer including a supply line and said expansible fluid operated valve means having a movable valve member controlling said supply line at the lowest point in the latter between the burner and said expansible fluid operated valve means.

4. In combination, a liquid fuel burner of the distillate type having a base and an annular groove therein and a combustion chamber above said groove and upwardly delivering air passage means in said base surrounded by said groove and delivering along said combustion chamber, and also having a vaporizer heated by said base for supplying vaporized fuel to said groove during normal operation, means for supplying liquid fuel to said vaporizer during said normal operation while maintaining a low pressure constant level supply supplying a limited amount of fuel within the maximum vaporizing capacity of said vaporizer when the burner is at maximum operating temperature, and expansible fluid operated temperature responsive valve means having a fuel passage controlled thereby and located in

said supplying means below the level of the fuel in said vaporizer and also having a controlling member controlling the flow through said passage and operative gradually as temperature changes affect the expansible fluid in said valve means for maintaining a continuous flow of fuel to said vaporizer while gradually and minutely varying the amount of fuel supplied to said vaporizer and maintaining said base and vaporizer at a sufficient temperature during said normal operation to vaporize the fuel being fed to said vaporizer.

5. In combination, a liquid fuel burner of the distillate type having a base and radially communicating annular grooves therein and combustion chambers above said grooves and upwardly delivering air passages in said base between said grooves and delivering between said combustion chambers, and also having a vaporizer heated by said base for supplying vaporized fuel to said grooves during normal operation, means for supplying liquid fuel to said vaporizer during said normal operation while maintaining a low pressure constant level supply including a manually adjustable valve means for limiting the flow of fuel supplied to an amount within the maximum vaporizing capacity of said vaporizer when the burner is at maximum operating temperature, and expansible fluid operated temperature responsive valve means having a fuel passage controlled thereby and located in said supplying means below the level of the fuel in said vaporizer and also having a controlling member controlling the flow through said passage and operative gradually as temperature changes affect the expansible fluid in said valve means for maintaining a continuous flow of fuel while gradually varying the amount of fuel supplied to said vaporizer during normal operation, said fuel passage and controlling member having cooperating means for varying the fuel supply minutely adjacent the point of cut-off of said expansible fluid operated valve means and thereafter more rapidly increasing the rate of fuel flow while reducing the necessary stroke of said valve means and while maintaining said supply within the limits of vaporization by said vaporizer at different operating temperatures and maintaining said base and vaporizer at a sufficient temperature during said normal operation to vaporize the fuel being fed to said vaporizer.

LYNN O. SELBY.
